Fig. 2.

Fig. 3.

Fig. 1.

W. W. WHIPPLESSON
PATENTED 1849
PHILA'D'A

Fig. 4.

270

Wm P. Crefon assignee of Crefon, Stuart and Seibert, of Philadelphia Pa.
Letters Patent. No. 270. Dated March. 12, 1850

The schedule referred to in these Letters Patent and making part of the same.

So whom it may concern:

Be it Known that we Wm P. Crefon, David Stuart and Peter Seibert, all of the County of Philadelphia in the State of Pennsylvania have invented or produced a new and useful design which is intended to ornament a Cast Iron Parlour Air tight Stove and do hereby declare that the following is a full and exact description of the same.

Fig 1. Represents the bottom or hearth plate very prettily carved on the outer edge with a succession of scrolls as at a. a. a. a. a. a. a. at each corner is a shell rosette as at c. c. c. c. with scroll work branching out forming the inside edge as at b. b. b. b. on the front of the plate we have a very pretty shell rosette as at d. inside of which the surface is carved into diamonds as at s. s.

Fig 2. Represents the top plate very prettily carved on the outer edge with a succession of leaves and scrolls as at a. a. a. a. a. at each corner is a shell rosette as at c. c. c. c. which branches out into leaves and scroll work. as at b. b. b. b. b. b. on each side we have a pretty shell rosette with leaves entwined as at e. e. in the centre we have a rosette as at f. enclosed in a bead as at g. g. emanating from each side is a succession of scroll work as at h. h. h. h.

Fig. 3. Represents the side ornamented on each side with a beautiful rosette with scroll work emanating therefrom as at a. a. a. a. inside is a bead or chain work as represented at b. b. b. b. in the centre of the side is a rosette as at c. enclosed by a very pretty leaved scroll work as at d. d. d. d. to the left of which is a very neat scroll work as at f. f. on the right of the centre we have represented a very pretty leave scroll work crowned with a wreath of flowers as at g. g. g. g.

Fig. 4. Represents the side plate with a rosette and scrolls emanating therefrom as at a. a. a. a. inside of which is a chained bead work as at b. b. b. b. enclosed between said bead work and divided by two columns of scroll work as at c. c. c. c. we have three very beautiful designs of leaves scroll work and flowers as represented at d, d, d, d, d around the ventilator is a prettily carved circle as at f, f.

Des. 270

D

Fig. 5. Represents the foot very prettily designed with shell rosette and scroll work as at a, a, a —

We have thus described the ornamental design which we claim as our invention or production and desire to secure by Letters Patent the design for a stove called a Cast Iron Parlor Air Tight herein fully described and represented in the accompanying drawings.

Witness Present.
John K. Sappington
Sam'l H. Young

Ex-m.

Wm. P. Crelson
David Stuart
Peter Seibert

770